UNITED STATES PATENT OFFICE.

EDWARD EVANS, OF QUINCY, ILLINOIS.

STOVE-LID PATTERN.

SPECIFICATION forming part of Letters Patent No. 374,147, dated November 29, 1887.

Application filed August 29, 1887. Serial No. 248,206. (Model.)

To all whom it may concern:

Be it known that I, EDWARD EVANS, a citizen of the United States, residing at Quincy, in the county of Adams and State of Illinois, have invented a new and useful Pattern for the Molding of Stove-Lids, of which the following is a specification.

My invention relates to an improvement in patterns for the molding of stove-lids in which slides are used to make the impressions for molding the projections in the core-seat. I accomplish this object by the mechanism illustrated in the accompanying drawings, in which—

15 Figure 1 is a face view of the pattern with the slides pushed out into the core-seat as they are when the impression is taken; Fig. 2, a back view of the pattern when the slides are in the core-seat as before; Fig. 3, a sectional view 20 of the pattern. Fig. 4 is a detail plan view, one of the plates *b* being removed. Fig. 5 is a detail sectional view taken through one of the slides.

Similar letters refer to similar parts throughout the several views.

25 *a* is the core-seat, in which the hook is placed to raise the lid.

b *b* are plates dovetailed into the face of the pattern and made to slide out into the core-seat for the purpose of cleaning out the places 30 or ways in which the slides work.

c c are the slides.

d d are the pins to draw the slides out with.

The slides *c c* are made with shoulders *h*, as may be seen in Fig. 3, which work under the 35 plates *b b* and in slots in the pattern and abut against walls of the slots to keep the slides from being drawn out too far.

g g are plates riveted on the under side of the pattern to hold the slides in place. 40

The slides are pushed out into the core-seats, as seen in Fig. 1, as far as the pins *d d* will allow, and the face impression of the pattern is made in the sand. The mold and pattern are then inverted and the slides drawn out until 45 the shoulders *h* strike the iron under the plates *b b*. The pattern may then be lifted out of the sand mold.

I am aware that prior to my invention stove-lids have been molded by patterns having slides 50 working into the core-seat.

What I claim as my invention, and desire to secure by Letters Patent, is—

A stove-lid pattern having a core-seat and a way, a pin arranged in the way and adapted 55 to be projected into and out of a core-seat, and a removable cover for the way.

EDWARD EVANS.
